Des. 202,873
Patented Nov. 16, 1965

202,873

POWER OPERATED TOOTHBRUSH HANDLE

John Lowell Husted, Case Hill Road,
Sterling Junction, Mass.

Filed Jan. 22, 1965, Ser. No. 83,536

Term of patent 14 years

(Cl. D9—2)

FIG. 1

FIG. 2

FIG. 3

FIG. 4

FIG. 1 is a perspective view of a power operated toothbrush handle, showing my new design.

FIG. 2 is a top view thereof.

FIG. 3 is a side elevational view thereof.

FIG. 4 is an end view thereof.

I claim:

The ornamental design for a power operated toothbrush handle, as shown.
